(57) **CLAIM**

The ornamental design for a trailer lock, as shown and described.

DESCRIPTION

FIG. 1 is a front top right perspective view of a trailer lock showing my new design;

FIG. 2 is a rear bottom left perspective view thereof;

FIG. 3 is a rear bottom right perspective view thereof;

FIG. 4 is a rear top left perspective view thereof;

FIG. 5 is a front elevational view thereof;

FIG. 6 is a rear elevational view thereof;

FIG. 7 is a left elevational view thereof;

FIG. 8 is a right side view thereof;

FIG. 9 is a top side view thereof; and,

FIG. 10 is a bottom plan view thereof.

The broken lines in the figures are for the purposes of illustrating portions of the trailer lock, which form no part of the claimed design.
